FRANCIS J. FARRELLY AND ALFRED GREINER, OF HARTFORD, CONNECTICUT.

X-RAY TUBE.

1,276,196.

Specification of Letters Patent. Patented Aug. 20, 1918.

Application filed January 25, 1916. Serial No. 74,134.

To all whom it may concern:

Be it known that we, FRANCIS J. FARRELLY and ALFRED GREINER, citizens of the United States, and residents of Hartford, 5 county of Hartford, State of Connecticut, have invented certain new and useful Improvements in X-Ray Tubes, of which the following is a specification.

This invention relates to X-ray tubes, and 10 particularly to a novel construction and arrangement of the cathode end of the tube having for its object the elimination to as great an extent as possible of the agencies that work within the tube tending to cause 15 a break of the glass bulb at the point where the cathode neck joins the bulb.

In the drawings—

Figure 1 is a side view of an X-ray tube equipped with our invention. 20 Fig. 2 is a sectional view of the cathode end of the tube on an enlarged scale.

Referring to the drawings, *a* denotes the main bulb, *b* the cathode neck, and *c* the anode neck; *d* is the anode, *e* the cathode, 25 surrounded by a metallic sleeve *5* out of electrical connection therewith, said sleeve being supported from the walls of the cathode neck by projections *6* therefrom entering depressions or apertures *7* in the sleeve. 30 *10* denotes the cathode stem embedded in insulating material, indicated here as glass *11*, on the outside of which there is fitted a metallic covering *12* in the form of a tube of proper metal, as aluminum. These three 35 parts, the stem, insulation, and metallic tube, are fitted rather closely together, and the tube *12* is not in electrical contact with the cathode *e* or the stem *10*. *15* denotes the exterior terminal of the tube which is connected with the cathode. *20* denotes a wire 40 of conducting material connected with the sleeve *12* and sealed through the end of the

cathode neck as at *21*, adjacent to the terminal *15*. This forms a conductive path for any electrical manifestations which build 45 up or accumulate within the cathode neck, permitting them to escape outside the tube and discharge over onto the terminal *15*. This causes to a large extent the dissipation of electrical manifestations within the cathode neck, and the sleeve *5* protects the wall 50 of the cathode neck against a concentrated bombardment of any electrical manifestations which are not discharged on the exterior of the tube. 55

As a result of this construction it has been found that tubes equipped with this invention operate with great steadiness, and that the overheating of the cathode neck is very largely eliminated, at least overheating to 60 such an extent as might cause the cracking of the tube at this point. The best results have been attained by the combined use of the sleeve and the discharge terminal.

We claim as our invention:—

1. In an X-ray tube a cathode stem supporting the cathode and connected with an exterior terminal, a glass shield surrounding said stem, a metallic member carried by said shield, and a conductor from said metallic member leading to the exterior of said tube and into co-operative relationship with said exterior terminal. 65

2. In an X-ray tube a cathode stem supporting a cathode, a covering of electrically 75 insulating material on said stem, a metallic member carried by said covering out of electrical contact with said cathode and stem, and a conductor from said metallic member leading to the exterior of said tube 80 and into co-operative relationship with said exterior terminal.

FRANCIS J. FARRELLY.
ALFRED GREINER.
